CARBAMYLALKYL PHOSPHATES AND
METHOD OF PREPARATION

Jack T. Cassaday and Erick I. Hoegberg, Stamford, and Bruce D. Gleissner, Riverside, Conn., assignors to American Cyanamid Company, New York, N. Y., a corporation of Maine

No Drawing. Application February 4, 1948,
Serial No. 6,348

13 Claims. (CL 260—461)

1

The present invention relates to new and useful organic phosphate compounds and the method of preparation thereof.

These new compounds are phosphate esters which conform to the general formula

in which R_1 and R_2 are chosen from the group consisting of alkyl, aralkyl, and aryl (in this specification and claims where the words aralkyl and aryl are used, they are intended to mean aralkyl hydrocarbon and aryl hydrocarbon respectively) radicals, R_3 and R_4 are members of the group consisting of hydrogen, alkyl, hydroxy-alkyl, aryl, and nitroaryl (in this specification and claims the word nitroaryl is intended to mean nitro substituted aryl hydrocarbon) radicals, X_1 , X_2 , and X_3 are members of the group consisting of sulfur and oxygen, and m represents a small whole number.

In the new compounds, R_1 and R_2 may be the same or different radicals. Furthermore, it is to be understood that when R_1 and R_2 stand for alkyl radicals, they represent both the straight chain and branch chain, the saturated and unsaturated, and the cycloaliphatic hydrocarbon radicals. The R_1 and R_2 radicals may also carry halogen substituents, particularly chlorine and bromine. Typical examples of these radicals are methyl, ethyl, n-propyl, isopropyl, isobutyl, sec-amyl, n-hexyl, 2-ethylhexyl, n-octyl, n-decyl, n-dodecyl, oleyl, cetyl, ceryl, allyl, bromomethyl, 2-chloroethyl, cyclohexyl, benzyl, phenyl, p-chlorophenyl, o, m and p-nitrophenyl.

The compounds of this invention possess general pest-control characteristics, including insecticidal, rodenticidal, and fungicidal properties. They may also be employed as corrosion inhibitors, plasticizers, flotation agents, and petroleum additives.

The phosphate esters of the above general formula, when the symbol X_3 stands for oxygen, may be readily prepared by reacting a phosphate of the general formula:

2

in which R_1 , R_2 , X_1 , and X_2 have the meaning shown above, and Y represents an alkali-forming metal, with a halogen-substituted amide of the general formula

10 in which R_3 , R_4 , and m have the meaning shown above, and Z is a member of the group consisting of chlorine and bromine.

The term "alkali-forming metal" as used in this specification and in the appended claims is intended to cover the alkali metals (including ammonium), and the alkaline earth metals.

15 A typical reaction in which sodium O,O-diethyl dithiophosphate is reacted with chloroacetamide to produce S-carbamylmethyl O,O-diethyl dithiophosphate may be illustrated as follows:

20 High yields of the desired products are obtained by carrying out the reaction in the presence of a solvent. Such solvents include water, the low molecular weight aliphatic monohydric alcohols, the ketones such as, for example, acetone, methyl ethyl ketone, methyl isobutyl ketone, methyl benzyl ketone, cyclohexanone, acetophenone, and the like; aliphatic esters such as ethyl acetate, amyl acetate, 2-ethylhexyl acetate, methyl propionate, methyl butyrate, ethyl butyrate, and isopropyl butyrate; saturated aliphatic nitriles such as acetonitrile and propionitrile; dioxane, nitrobenzene, chlorobenzene, toluene, xylene, chloroform, carbon tetrachloride, 1,2-dimethoxyethane, and the trialkyl phosphates such as trimethyl phosphate, triethyl phosphate, and triisopropyl phosphate.

25 The reaction is preferably carried out at a temperature within the range of from about 20° to 150° C. However, temperatures outside of this range may be employed depending upon the type of reactants and solvents utilized.

An alternative method of preparing the above compounds consists in employing in lieu of the alkali-forming metal phosphate the corresponding acid and a basic alkali-forming metal compound, the latter having sufficient alkalinity to neutralize said acid. Obviously, this procedure avoids the initial preparation and isolation of the alkali-forming metal phosphate. Such basic alkali-forming metal compounds include sodium carbonate, potassium carbonate, barium carbonate, magnesium carbonate, lithium carbonate, sodium hydroxide, potassium hydroxide, calcium hydroxide, strontium hydroxide, magnesium hydroxide, sodium hydroxide, sodium borate, tri-potassium arsenate, tripotassium arsenite, sodium pyrophosphate, magnesium pyrophosphate, potassium pyrophosphate, barium phosphate, tri-sodium phosphate, and the like.

Employing the above procedure in the preparation of S-(N,N-diethyl carbamyl) methyl O,O-diisopropyl dithiophosphate, the reaction may be illustrated as follows:

The phosphate esters of the above general formula, when the symbol X_3 stands for sulfur, may be prepared by reacting a cyanoalkyl phosphate of the general formula

in which R_1 , R_2 , X_1 , X_2 , and m have the meaning shown above, with either hydrogen sulfide or a mercaptan, preferably in a closed vessel under pressure.

The cyanoalkyl phosphates utilized in the preceding reaction may be prepared by reacting a phosphate of the general formula

in which R_1 , R_2 , X_1 , X_2 , and Y have the meaning shown above, with a halogen-substituted nitrile of the general formula $Z-(CH_2)_m-CN$ in which m and Z have the meaning shown above.

The following examples will further illustrate the invention.

Example 1

41.6 grams (0.2 mol.) of sodium O,O-diethyl dithiophosphate, 18.7 grams (0.2 mol.) of chloroacetamide, and 250 cc. of acetone were mixed together and allowed to stand at room temperature (20° C.) for 24 hours. The precipitated sodium chloride was filtered off and the filtrate heated under vacuum to remove the acetone. The reac-

ual crystalline product, S-carbamylmethyl, O,O-diethyl dithiophosphate, weighing 46 grams (95% yield) was recrystallized from 125 cc. of carbon tetrachloride. The recrystallized product was a colorless crystalline solid, melting at 57°-58° C.

Example 2

The procedure of Example 1 was employed, using 62.4 grams of sodium O,O-diethyl dithiophosphate, 51 grams of chloroacetanilide, and 400 cc. of acetone. 91 grams of crude O,O-diethyl S-(N-phenylcarbamyl) methyl dithiophosphate were obtained. After recrystallization from heptane, the product was a colorless crystalline material melting at 85°-87° C.

Example 3

The procedure of Example 1 was employed using 41.6 grams of sodium O,O-diethyl dithiophosphate, 42.9 grams of alpha-chloro-4-nitroacetanilide, and 250 cc. of acetone. 69 grams (95% yield) of O,O-diethyl S-(N-p-nitrophenyl carbamyl) methyl dithiophosphate were obtained. After recrystallization from 500 cc. of carbon tetrachloride, the product was a colorless crystalline material melting at 109°-110° C.

Example 4

62.4 grams of sodium O,O-diethyl dithiophosphate, 32.3 grams of beta-chloropropionamide, and 400 cc. of acetone were mixed together and allowed to stand at room temperature for 24 hours. The precipitated sodium chloride was filtered off and the filtrate heated under vacuum to remove the acetone. The residual product, S-2-carbamylethyl O,O-diethyl dithiophosphate, weighing 65 grams, was a clear, light brown liquid having a refractive index n_D^{25} 1.5230.

Example 5

The procedure of Example 4 was employed using 14.4 grams of sodium O,O-diethyl dithiophosphate, 7.4 grams of beta-chloropropionanilide, and 100 cc. of acetone. The residual product, O,O-diethyl S-(2-N-phenylcarbamyl) ethyl dithiophosphate, weighing 20.8 grams (90% yield), was an amber-colored oil having a refractive index n_D^{25} 1.5468.

Example 6

The procedure of Example 4 was employed using 62.4 grams of sodium O,O-diethyl dithiophosphate, 37.1 grams of alpha-chloro-N-(hydroxymethyl) acetamide, and 250 cc. of acetone. The mixture was heated under reflux for a period of 6 hours. The residual product, O,O-diethyl S-(N-hydroxymethyl) carbamylmethyl dithiophosphate, was a straw-colored, viscous liquid having a refractive index n_D^{25} 1.5372.

Example 7

42.9 grams of O,O-dimethyl dithiophosphoric acid were added slowly to a well-agitated mixture of 28.7 grams of anhydrous sodium carbonate suspended in 100 cc. of methyl isobutyl ketone. The mixture was then heated to about 65° C. and 25.3 grams of chloroacetamide were added. The resulting mixture was held at 80° C. for one hour with continued stirring, then cooled to room temperature and filtered. The filtrate was washed twice with water, dried over anhydrous sodium sulfate, and filtered. The filtrate was heated under vacuum to remove the methyl isobutyl ketone. The residual product, S-carbamylmethyl O,O-dimethyl dithiophosphate, was a colorless crystalline solid melting at 60°-62° C.

Example 8

The procedure of Example 7 was employed using 100 grams of O,O-diethyl dithiophosphoric acid, 53 grams of anhydrous sodium carbonate, 300 cc. of methyl isobutyl ketone, and 46.8 grams of chloroacetamide. The residual product, S-carbamylmethyl O,O-diethyl dithiophosphate, was a colorless crystalline material melting at 57° C.

Example 9

48.4 grams of O,O-dibutyl dithiophosphoric acid were added slowly to a well-agitated mixture of 21.2 grams of anhydrous sodium carbonate suspended in 200 cc. of acetone. 18.7 grams of chloroacetamide were then added. The reaction mixture was stirred for two hours, allowed to stand at room temperature (20-22° C.) for 24 hours, filtered, and the filtrate stripped of solvent under vacuum. The residual brown oil was washed twice with dilute sodium carbonate solution, then with water, and dried over anhydrous sodium sulfate. The product, O,O-di-n-butyl S-carbamylmethyl dithiophosphate, was an amber-colored, viscous oil having a refractive index n_D^{25} 1.5111.

Example 10

The procedure of Example 9 was employed using 28.2 grams of O,O-diphenyl dithiophosphoric acid, 10.6 grams of anhydrous sodium carbonate, 100 cc. of methyl isobutyl ketone, and 9.4 grams of chloroacetamide. The reaction mixture was stirred and heated at 75°-80° C. for a period of 4 hours. 23 grams of S-carbamylmethyl O,O-diphenyl dithiophosphate were obtained. The product was a red, viscous oil having a refractive index n_D^{25} 1.5988.

Example 11

18.3 grams of n-butyl amine, 26.5 grams of anhydrous sodium carbonate, and 200 cc. of methyl isobutyl ketone were mixed together and cooled in an ice-bath. 28.3 grams of chloroacetyl chloride were added with stirring during a period of one hour, the temperature being held at 10°-2° C. The mixture was then warmed slowly to 5° C. and maintained at this temperature for ½ hours, after which it was allowed to cool to 0° C. 26.5 grams of anhydrous sodium carbonate were then added, followed by the addition of 50 grams of O,O-diethyl dithiophosphoric acid. The mixture was held at 85° C. for 3½ hours, cooled to room temperature, and filtered. The filtrate was washed several times with water, then with saturated sodium bicarbonate solution, and dried over anhydrous sodium sulfate. The methyl isobutyl ketone was removed by distillation under reduced pressure. The residual product, S-(N-butylcarbamyl)methyl O,O-diethyl dithiophosphate, was a light brown oil having a refractive index n_D^{25} 1.5057.

Example 12

56.1 grams of potassium hydroxide were dissolved in 400 cc. of ethyl alcohol cooled in an ice-bath. 86 grams of diethyl chlorophosphate were added drop-wise with stirring, the temperature being held at 10°-15° C. The mixture containing potassium diethyl phosphate and precipitated potassium chloride was warmed to 35° C. 70 46.8 grams of chloroacetamide were then added. The reaction mixture was heated to 50° C. and stirred for ½ hour, then allowed to stand at room temperature (20-22° C.) for 36 hours. The precipitated potassium chloride was removed 75

by filtration and the filtrate was stripped of ethyl alcohol by distillation under vacuum. The residual product, carbamylmethyl diethyl phosphate, was a colorless oil having a refractive index n_D^{25} 1.4280.

Example 13

62.6 grams of potassium O,O-diethyl thiophosphate and 28.1 grams of chloroacetamide were dissolved in 250 cc. of methyl ethyl ketone. The mixture was heated at 60° C. for 2 hours, cooled to room temperature, and filtered. The filtrate was stripped of the methyl ethyl ketone by distillation under vacuum. The residual product, carbamylmethyl O,O-diethyl thiophosphate, was obtained in quantitative yield as an amber-colored, viscous liquid having a refractive index n_D^{25} 1.4883.

Example 14

50 grams of S-cyanomethyl O,O-diethyl dithiophosphate and 7.6 grams of hydrogen sulfide were reacted together in a closed vessel in 100 cc. of toluene in the presence of 1 gram of triethyl amine (catalyst) at 60° C. under a pressure of 100 lbs. per sq. in. for a period of 20 hours. The reaction mixture was poured into a shallow open vessel and the toluene allowed to evaporate off, leaving a mixture of yellow crystals and a brown oil. The crystals were removed by filtration, and recrystallized from a 25% toluene-75% hexane mixture with a small quantity of decolorizing charcoal. The product, O,O-diethyl S-thiocarbamylmethyl dithiophosphate, was a colorless crystalline material melting at 46°-47° C.

The phosphate esters of this invention may be employed in controlling many types of insects and mites such as, for example, the black bean aphid, green peach aphid, pea aphid, chrysanthemum aphid, greenhouse thrips, California red scale, citrus red spider, greenhouse red spider, milkweed bug, mealy bug, sow bug, German cockroach, southern army worm, yellow fever mosquito, malarial mosquito, Mexican bean beetle, confused flour beetle, and black carpet beetle.

These new compounds may also be used in combination with insecticides such as lead arsenate, nicotine, rotenone, pyrethrum, benzene hexachloride, 1,1,1-trichloro-2,2-di(p-chlorophenyl)-ethane, dodecyl thiocyanate, phenothiazine, and the like; with fungicides such as sulfur, various copper compounds, mercury salts, and the like; and with various types of plant foods and fertilizers.

While the invention has been described with particular reference to specific embodiments, it is to be understood that it is not to be limited thereto, but is to be construed broadly and restricted solely by the scope of the appended claims.

We claim:

1. Phosphate esters of the general formula

in which R₁ and R₂ are chosen from the group consisting of alkyl, aralkyl, and aryl radicals, R₃ and R₄ are members of the group consisting of hydrogen, alkyl, hydroxyalkyl, aryl, and nitro-aryl radicals, X₁, X₂, and X₃ are members of the group consisting of sulfur and oxygen, and m represents a small whole number.

2. S-carbamylmethyl O,O-diethyl dithiophosphate.
3. S-carbamylmethyl O,O-dimethyl dithiophosphate.
4. O,O-diethyl S-(N-hydroxymethyl) carbamylmethyl dithiophosphate.
5. A method of preparing a phosphate ester of the general formula

in which R_1 and R_2 are chosen from the group consisting of alkyl, aralkyl, and aryl radicals, R_3 and R_4 are members of the group consisting of hydrogen, alkyl, hydroxyalkyl, aryl, and nitroaryl radicals, X_1 and X_2 are members of the group consisting of sulfur and oxygen, and m represents a small whole number, which includes the step of reacting a phosphate of the general formula

in which R_1 and R_2 are chosen from the group consisting of alkyl, aralkyl, and aryl radicals, X_1 and X_2 are members of the group consisting of sulfur and oxygen, and Y represents an alkali-forming metal, with a halogen-substituted amide of the general formula

in which R_3 and R_4 are members of the group consisting of hydrogen, alkyl, hydroxyalkyl, aryl, and nitroaryl radicals, m represents a small whole number, and Z is a member of the group consisting of chlorine and bromine.

6. The method of claim 5 in which the reaction is carried out in the presence of a solvent.

7. The method of claim 5 in which the reaction is carried out at a temperature within the range of from about 20°-150° C.

8. A method of preparing a phosphate ester of the general formula

in which R_1 and R_2 are chosen from the group consisting of alkyl, aralkyl, and aryl radicals, R_3 and R_4 are members of the group consisting of hydrogen, alkyl, hydroxyalkyl, aryl, and nitroaryl radicals, X_1 and X_2 are members of the group

consisting of sulfur and oxygen, and m represents a small whole number, which includes the step of reacting together a halogen-substituted amide of the general formula

in which R_3 and R_4 are members of the group consisting of hydrogen, alkyl, hydroxyalkyl, aryl, and nitroaryl radicals, m represents a small whole number, and Z is a member of the group consisting of chlorine and bromine, an acid phosphate of the general formula

in which R_1 and R_2 are chosen from the group consisting of alkyl, aralkyl, and aryl radicals, and X_1 and X_2 are members of the group consisting of sulfur and oxygen, and a basic alkali-forming metal compound having sufficient alkalinity to neutralize the acid phosphate.

30. 9. The method of claim 8 in which the basic alkali-forming metal compound is sodium carbonate.

10. The method of claim 8 in which the reaction is carried out in the presence of a solvent.

35. 11. A method of preparing S-carbamylmethyl O,O-diethyl dithiophosphate which includes the step of reacting together O,O-diethyl dithiophosphoric acid, sodium carbonate, and chloroacetamide in the presence of a ketone.

40. 12. A method of preparing S-carbamylmethyl O,O-dimethyl dithiophosphate which includes the step of reacting together O,O-dimethyl dithiophosphoric acid, sodium carbonate, and chloroacetamide in the presence of a ketone.

45. 13. A method of preparing O,O-diethyl S-(N-hydroxymethyl) carbamylmethyl dithiophosphate which includes the step of reacting together sodium O,O-diethyl dithiophosphate and alpha-chloro-N-(hydroxymethyl) acetamide in the presence of a ketone.
